(57) CLAIM

The ornamental design for a display panel or screen with graphical user interface, as shown and described.

DESCRIPTION

FIG. 1 is a front elevational view of a display panel or screen with graphical user interface showing our new design; and, FIG. 2 is a front elevational view of a display panel or screen with graphical user interface showing our new design, wherein the image of FIG. 2 is an alternative image of the image of FIG. 1, in which an unclaimed background image shown in broken lines (letter "A") is overlapping with one (top row) of the circle images, as if the circle image looks transparent or semi-transparent and as if one can see the background image through the one of the circle images, and in which another unclaimed background image shown in broken lines (letter "A") is overlapping with another one (middle row) of the circle images, as if the circle image looks opaque and as if one cannot see the background image through the another one of the circle images.

The broken lines showing of a display panel or screen and other elements form no part of the claimed design.
